UNITED STATES PATENT OFFICE.

JOHN WALTON, OF PHILIPSBURG, PENNSYLVANIA.

COAL-MINING MACHINE.

SPECIFICATION forming part of Letters Patent No. 355,284, dated December 28, 1886.

Application filed March 20, 1886. Serial No. 195,985. (No model.)

To all whom it may concern:

Be it known that I, JOHN WALTON, a citizen of the United States, residing at Philipsburg, in the county of Centre and State of Pennsylvania, have invented certain new and useful Improvements in Coal-Mining Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has for its object to provide an improved and novel construction of coal-mining machines, which combines in its construction and operation a high degree of efficiency, utility, and ease of adjustment with a ready 20 adaptation to the purpose contemplated; and my improvements consist, essentially, of the details of construction and general arrangement of parts, all as will be hereinafter fully described, and specifically designated in the 25 claims.

In the accompanying drawings, Figure 1 represents a front elevation of my improved apparatus; Fig. 2, a vertical transverse section taken on the line *x x* of Fig. 1, and Fig. 3 an 30 end elevation.

Similar letters of reference occurring on the several figures indicate like parts.

The frame of my improved machine is preferably rectangular in shape, being composed 35 of the end uprights, A A', united together by the cross-beams B B' and side rails, C C', each of the parts being detachably secured together by means of suitable connecting bolts or screws to permit of the same being taken readily apart 40 for transportation from one place to another, or as easily placed together to form the frame or standard upon which the operative mechanism is supported, said frame or standard being secured in the desired position by means 45 of the spurs or points *a* upon the lower corners of each of the end uprights, A A', and by the chisel-pointed ends of the screw-threaded rods *b* upon the upper part of the said end uprights, the lower points or spurs, *a*, projecting into the 50 floor of the coal-passage, and the points of the screw-threaded rods *b* projecting into the roof

of the same. The screw-threaded rods *b* fit into correspondingly-threaded openings in the cross-beams B' B' of the end uprights, A A', and, being provided at their lower ends with 55 a hand-wheel, *b'*, are capable of being adjusted up or down, according to the height of the roof. By turning the hand-wheels *b'* the rods *b* are moved vertically in their threaded journals, to project into the same to hold the frame 60 or standard in a rigid position during the operation of the machine.

The lower side rails, C, one on each side of the frame, are each provided upon their upper surfaces with a V-shaped or other suitably-shaped flange, *c*, extending the entire length of the rail, while the upper side rails, C', have an arched groove, *c'*, upon their lower surfaces for the reception between the said upper and lower rails of the carriage D, the lower and 70 upper ends of which conform in shape to the said flange *c* and groove *c'*, to permit of the said carriage D being held between said side bars, C C', in position to be readily moved forward or back within the limits of said frame 75 or standard.

Near the lower end of the carriage D, and rigidly secured thereto, are provided plates *d*, one on each side, having central openings for the passage of a screw-threaded rod, E, the ends 80 of which are secured between the end uprights, A A', by means of headed bolts *e*, passing through the same and fastened in place by suitable nuts, as fully shown in Fig. 3.

At each end of the screw-threaded rod E, 85 and adapted to move upon the same, are provided hand-wheels F, having corresponding screw-threaded central openings for the reception of the rod E, for propelling the carriage in either direction within the limits of the 90 frame or standard.

Suitably journaled in the upper part of the carriage D is provided the driving-wheel G, which may be operated by hand or other suitable motive power, and the cogs or teeth of 95 which mesh into the cogs or teeth of the small pinion G', which is also suitably journaled in the sides of the carriage D, beneath the driving-wheel G. The axis of the said pinion G' is hollow from end to end for the reception 100 therein of the outer end or shank of the coal cutter or drill H, which may be held at the de-

sired position in the axle of said pinion by means of the set-screws *g*, as fully shown in Fig. 2.

In the operation of my improved apparatus 5 the cutting-tool first drills or bores a hole about three feet deep into the coal. Then the same tool changes its course from right to left, or vice versa, and cuts across the face of the coal as the carriage is propelled along the screw-threaded rod *E*, the depth of the cut for the entire length of the frame remaining three feet deep where steam-power is used; but where hand-power is employed such cut can be only eighteen inches deep, necessitating the carriage 15 being run back to make another cut of like depth, which makes three feet deep, or equal to one cut by steam-power.

Having thus described my invention, I claim as new and useful—

20 1. A coal-mining machine consisting of a frame having standards with top and base horizontal side rails secured thereto, rigid base projecting points, adjustable screw-threaded

and pointed vertical rods journaled to the face of said standards and provided with end adjusting-wheels, in combination with a carriage-frame having gear-wheels journaled within, as described, and provided with end flanges and grooves adapted to loosely fit and move horizontally on said rails, substantially as shown 30 and specified.

2. In a coal-mining machine, a vertical carriage-frame provided with a gear drive-wheel, and a pinion with hollow axle, as a drill-chuck, and in which the drill is secured, in combination with a carriage-frame having top and base horizontal beveled bearings adapted to receive and loosely hold by end bearing said carriage-frame, substantially as shown and specified. 35

In testimony whereof I affix my signature in presence of two witnesses.

JOHN WALTON.
